United States Patent Office.

ELEMIR J. NEY, OF LOWELL, MASSACHUSETTS, ASSIGNOR TO LOWELL MANUFACTURING COMPANY, OF SAME PLACE.

Design No. 2,762, dated August 20, 1867.

DESIGN FOR A CARPET PATTERN.

The Schedule referred to in these Letters Patent and making part of the same.

TO ALL WHOM IT MAY CONCERN:

Be it known that I, ELEMIR J. NEY, of Lowell, in the county of Middlesex, and State of Massachusetts, have originated and designed a new Pattern for Carpets or other fabrics, of which the following is a full, clear, and exact description, reference being had to the accompanying drawings, making part of this specification.

A, in the centre, is a cross, resting on diamond B. C C C C are four halves of small blocks; the form of which is shown in the design. D D D D are bars, connecting diamond B and blocks C C C C. The rest of the design is occupied by lace-work, sprigs, and rosettes, as shown in the design.

The colors employed for the different portions of the design may be varied to suit the taste and wish of the manufacturer.

Claim.

What I claim as my invention, and desire to secure by Letters Patent, is—
The design or pattern for carpets or other fabrics herein set forth.
